UNITED STATES PATENT OFFICE

126,423

DESIGN FOR A MARKSMANSHIP PRACTICING APPARATUS

Clarence A. Schuyler, Chicago, Ill., assignor to H. C. Evans & Company, Inc., Chicago, Ill., a corporation of Illinois

Application January 13, 1941, Serial No. 98,006

Term of patent 3½ years

To all whom it may concern:

Be it known that I, Clarence A. Schuyler, a citizen of the United States and a resident of Chicago, in the county of Cook and State of Illinois, have invented a new, original, and ornamental Design for a Marksmanship Practicing Apparatus, of which the following is a specification, reference being had to the accompanying drawings, forming a part thereof, and in which:

Fig. 1 is a side elevational view of a marksmanship practicing apparatus showing my new design;

Fig. 2 is a view of the same from above in Fig. 1;

Fig. 3 is an end elevational view of the same as seen from the right in Fig. 1; and

Fig. 4 is an elevational view of the same as seen from the left in Fig. 1.

I claim:

The ornamental design for a marksmanship practicing apparatus, as shown.

CLARENCE A. SCHUYLER.
